UNITED STATES PATENT OFFICE.

FRANCIS L. MORGAN AND ARTHUR CLAIRE DEWEY, OF WASHINGTON, IOWA.

PARACHUTE CONTAINER.

Application filed May 3, 1923. Serial No. 637,570.

To all whom it may concern:

Be it known that we, FRANCIS L. MORGAN and ARTHUR CLAIRE DEWEY, citizens of the United States, residing at Washington, in 5 the county of Washington and State of Iowa, have invented new and useful Improvements in Parachute Containers, of which the following is a specification.

At times aeroplanes drop, resulting from 10 various causes, as, for instance, the engine going dead or due to the aeroplane traveling through a vacuum pocket.

It is, therefore, the purpose of the present invention to provide an improved safety appliance to be located on any part of the machine, preferably on the upper surface 15 of the top plane, and to be manipulated by the operator, in case of accident, so as to release a plurality of parachutes, which act, 20 when released, to allow the aeroplane to descend gradually.

Another purpose is to provide a safety appliance to avoid the foregoing catastrophe including a receptacle wherein a plurality 25 of parachutes is carried in nested formation, there being a passage formed through the receptacle or container, to permit of the passage of air therethrough in order to discharge and open the parachutes when released. Still another purpose is the provision 30 of the closures for the opposite ends of the container including means to be actuated by the operator for opening the closures to permit of the discharge and opening of the parachutes, due to the passage 35 of air through the space in the container.

A further purpose is the provision of means, such as a rope or a cable, or the like, for anchoring the series of parachutes to 40 the aeroplane, said rope, cable or the like being wound around a reel which is provided with suitable means to prevent the rope from unreeling too rapidly.

A still further purpose is the provision of 45 means for so mounting the container as to permit the same to change its position and allow the rope to unreel, in case the aeroplane makes a tail spin.

The invention comprises a structure, 50 which, at present, is deemed preferable. However, the invention is not to be limited or restricted to the details shown. In practice various changes and alterations may be necessary, consequently the right to such 55 changes and alterations that may be required as a result of reduction to practice

is claimed, provided they fall within the limits of what is claimed.

The invention comprises further features and combination of parts to be hereinafter set forth, shown in the drawings and claimed.

In the drawings:

Figure 1 is a perspective view of an aeroplane, showing a plurality of parachutes released and acting to support the machine in its descent;

Fig. 2 is an enlarged view in side elevation of a part of the body or fuselage of an aeroplane, showing the safety appliance as applied;

Fig. 3 is a sectional view of the container for the parachutes, on line 3-3 of Figure 2, showing the air passage, in order to illustrate the tapering contour thereof;

Fig. 4 is a longitudinal sectional view;

Fig. 5 is an enlarged view in side elevation of the container.

Referring to the drawings, 1 designates the body of the aeroplane and 2 the cockpit, 30 and 3 the struts for the support of the top plane 4.

Supported upon the plane 4 is a container 5 constructed of any suitable material, preferably aluminum or the like, and which 35 may be any suitable shape. Axially aligned pivots 6 connect the container to the upper forward edge of the top plane. These pivots are so located as to permit the container to reverse its position automatically, in case 40 the aeroplane makes a tail spin in the act of falling, so as to permit of the discharge and opening of the parachutes. To assist in causing the container to reverse its position a suitable fin 7 is connected to and carried 45 by the container. In case of a tail spin the air will contact with the fin and cause the container to tilt to a position just the reverse to that shown in Fig. 2.

The container is provided with interior 100 walls 8, so constructed and arranged as to cause a passage 9 to be formed. The wall of this passage is integrally connected to an end wall 10 of the container. A flanged opening 11 is formed in the wall 10, and 105 hinged in any suitable manner as at 12 is a closure 13, which acts to close the passage 9. The pivot 12 preferably consists of a transverse rod having an arm 14 at one end and an actuating crank arm 15 at the opposite end.

The opposite end of the container is open,

there being a closure 16 hingedly supported upon a rocking rod 17. Ordinarily the closures 13 and 16 are closed. One end of the rocking rod 17 has an arm 18. A connecting rod 19 connects the arms 14 and 18, so that when the rocking rod 12 is rotated by moving the crank arm 15 downwardly the two closures simultaneously open. In fact the movement of the arm 14 imparts a reciprocating movement to the connecting rod 19, which in turn opens the closure 16. In order to accomplish this result a suitable cable or rope 20 is attached to the crank arm 15, and has its other end terminating in a position close to the operator. In fact the other end may be connected to the side of the cock pit.

The wall 8 which causes the air passage 9 to be formed supports a plurality of parachutes 21, which are nested upon the exterior of the wall 8 and interconnected by ropes or cables 22. The spaces above and below the walls of the passage 9 are designed for the reception of the parachutes, when nested, so that when air passes through the passage 9 and the closures 13 and 16 open, the parachutes will be removed so that they may assume supporting positions upon an unauthorized descent of the aeroplane. The lower parachute is connected by a cable or rope 23, which in turn passes through the flanged opening 11 and is normally wound about a drum or reel 24, which is located in the cock pit of the body of the aeroplane. One end of the reel or drum has a brake wheel 25 with which a brake band 26 co-operates, in order to retard the movement of the drum, when the rope or the cable or the like is unreeled. One end of the brake band is preferably fixed, while the other end is attached to a suitable screw or other adjusting device 27, whereby the brake band may be tightened or loosened with respect to the brake wheel, for the purpose of governing the unreeling action of the rope.

The closures have suitable catches 28, which normally hold them in closed position. These catches are of such construction as to permit the passage of air to overcome their retaining action, so as to enable the closures to easily open in case of accident.

Should it be noted by the operator that the aeroplane is about to fall, either making a nose dive or a tail spin, the rope 20 may be actuated by imparting a pull thereon. This pulling action will overcome the catches, and cause the rod 12 to rock and the closure 13 to open, the rod 19 will in turn open the closure 16, the air will rush through the passage 9 and force the nested parachutes from the spaces above and below the passage 9 and cause them to automatically open. The parachutes will assume positions, such as shown in Fig. 1, and act to

support the aeroplane in its descent. In case the aeroplane makes a nose dive, the container 5 will remain in the position shown in Fig. 2, that is, engaging with the upper face of the top plane. However, in case of a tail spin, the container 5 will reverse its position, tilting upon the pivot 6, so as to permit the parachutes to automatically discharge and open.

In summarizing and by referring particularly to Fig. 4 it will be seen that three parachutes are nested in the space about the tapered air passage 9. One of the parachutes and preferably the smallest parachute is extended over the outlet of the tapered air passage 9 so that when the air passage is opened the rush of air through the same will cause the parachute at the outlet end of the air passage to be moved outwardly and opened. The movement of this first parachute to open in operative position will cause the other parachutes connected thereto to be immediately moved to open position as illustrated in Fig. 1. The container may now swing on its pivot so that it occupies a substantially vertical position.

The invention having been set forth, what is claimed is:

1. A safety appliance for flying machines comprising a parachute, a container receiving the parachute and having a gradually restricted air conduit extending longitudinally thereof and opening out through opposite ends of the container, the parachute being extended around and over the outlet end of the air conduit whereby the rush of air through the passage will open the parachute, a closure for the inlet end of the air passage, and means pivotally supporting the container.

2. A safety appliance for flying machines comprising a plurality of parachutes, a container receiving the parachutes and having an internally gradually restricted air passage extending longitudinally thereof and opening out through opposite ends of the container, one parachute being extended over the outlet end of the air passage whereby the rush of air through the passage will open the parachute extended over the air passage, closures for opposite ends of the container, means connecting the closures for simultaneous movement and operating means for the closures.

3. A safety appliance for flying machines comprising a plurality of parachutes, a container receiving the parachutes and having an internally gradually restricted air passage extending longitudinally thereof and opening out through opposite ends of the container, one parachute being extended over the outlet end of the air passage whereby the rush of air through the passage will open the parachute extended over the air

passage, closures for simultaneous movement, operating means for the closures and pivot means connected to end portion of said container.

- 5 4. A safety appliance for aeroplanes comprising a container provided with a central tapering air passage and having space for the reception for a plurality of connected parachutes, a closure for the intake end of 10 the passage, a closure for the outlet end of the passage, operative connections between the two closures, and means operatively con-

nected to one closure for opening the same and thereby simultaneously opening the other closure through the medium of the 15 operative connections between the two closures, one of said parachutes being extended over the outlet end of said tapering outlet passage.

In testimony whereof we affix our signatures.

FRANCIS L. MORGAN.
ARTHUR CLAIRE DEWEY.
